SLICE FOR PAPERMAKING MACHINERY

William M. Wilson, Morristown, N. J.

Application November 1, 1940, Serial No. 363,939

1 Claim. (Cl. 92—49)

This invention relates to paper making machinery and more particularly to an improved form of slice.

At different stages of the operation of forming the stock or stuff to paper, the water expressed from the stock and its carrying support or felt by the coating rolls accumulates in the angular space or recess at the entrance side of the cylindrical surfaces in front of their nipping points. This accumulated water must be kept close to the nipping point and removed, to prevent it from being absorbed or taken up by the wet stock or felt which would render the finished paper product defective and unsalable. Slices are used to prevent this water from running back on the felt. The accumulated water also tends to saturate the sheet of paper, resulting in dirty felts and crushing or flowering of the sheet. The slice of the present invention is primarily intended for use ahead of the primary or baby rolls and ahead of the first press rolls of a cylinder type of paper machine, but its application to other rolls or types of machines will be apparent to those skilled in the art.

An embodiment of the invention is shown in the accompanying drawings.

Fig. 1 is a fragmentary elevational view with parts shown in cross-section;

Fig. 2 is an end elevation of the slice;

Fig. 3 is a cross-section on line 3—3 of Fig. 6; 30 Fig. 4 is a fragmentary view of the journal mounting for the slice;

Fig. 5 is a side elevation of a series of primary rolls and a press roll with slice applied;

Fig. 6 is a top plan view of the slice, and

Fig. 7 is an end elevation of the slice.

In the several figures, 1 designates the standard or support for the primary rolls, and 2 the rolls. There are a series of these rolls comprising a part of the conventional cylinder paper machine. 3 designates the usual felts upon which the paper pulp or stuff is carried through the machine.

The invention of the present application resides in the improved slice, commonly used in such machines for disposing of the water accumulating adjacent the nip of the rolls. Slices as heretofore constructed have been found injurious to the felt, scarring it and causing the felt fibers to wear away and also picking up foreign matter which causes a felt to wear and weaken, rendering it defective and of short life.

The slice indicated generally by the numeral 4 comprises a strip of sheet metal in the form of a gutter extending across the width of the felt

10 to collect the accumulated water at the nip of the rolls and direct it over the edges of the felt. Said strip comprises a flat portion 4a engaging the surface of the felt and having its forward edge 15 bent or rounded inwardly as shown at 4b and the rear edge is also bent or rounded at 4c an arc of greater radius than the forward bend. The bent portions of the strip form the side walls of the gutter which are preferably of different heights for the purpose hereafter explained. This is the preferred construction, but the nature of the bends or rounded portions may of course be varied in character and proportions from that shown. The slice is provided with journals 4d and supported in journal bearings 4e in the standards 1. It will be seen that the slice is a trough-like structure and forms a gutter to collect and discharge by gravity the excess water expressed adjacent the nip of the rolls, the water being discharged from the gutter at the edges of the felt.

The rounded forward end prevents the slice from cutting into the felt and also prevents foreign matter from lodging between the felt and the slice. The higher rounded rear end prevents the collected water from splashing or overflowing the side of the gutter and also prevents lodgment of foreign matter and reduces wear.

The slice is preferably constructed of light weight stainless steel shaped and braced to give maximum rigidity to prevent bending and twisting. The light weight slice can be handled quickly and easily—a highly important feature in the operation of any paper machine.

35 In some situations it is necessary to provide the slice with a tensioning device, that is, a device which will exert pressure upon the forward end of the slice and cause it to engage the felt with more pressure at that point. Said tension device comprises, in the embodiment shown, a detachable hook 5 engaging the rear rounded end of the slice, a rod 6 connected with said hook and bearing upon the forward rounded end of the slice. A cable and turnbuckle or suitable means 7 is attached to the forward end of the rod and is attached to the machine frame or is otherwise tensioned to produce the stress on the slice. There is a tension device at each end of the slice, one only of the tension devices being shown in Fig. 1. As shown in Fig. 5, slices are provided for other rolls and it is obvious that the slices may be employed at any stage in the series of cylinders.

I claim:

In a paper making machine of the cylinder

and web type including press rolls and an endless felt for carrying the paper stock between the rolls, a slice comprising an open metal gutter and means for supporting the same on the felt in proximity to said rolls, the forward side of the gutter being located adjacent the nip of the rolls and having its edge rounded inwardly

to form a passageway for collecting the accumulated water at the nip of the rolls, the rear side of the slice also having its edge rounded inwardly to form a barrier to prevent splashing and overflow of the collected water.

WILLIAM M. WILSON.
